(57) CLAIM

The ornamental design for a bottle cap, as shown and described.

DESCRIPTION

FIG. 1 illustrates a right front perspective view of the bottle cap showing my new design, wherein the broken line showings of the illustration thereon are for illustrative purposes only and form no part of the claimed design;

FIG. 2 illustrates a front elevation view thereof, wherein the rear elevation view, the right side elevation view and the left side elevation view are mirror images of this view;

FIG. 3 illustrates a top view thereof;

FIG. 4 illustrates a bottom view thereof;

FIG. 5 illustrates a right front perspective view of a second alternative embodiment of the bottle cap showing my new design;

FIG. 6 illustrates a front elevation view of FIG. 5, wherein the rear elevation view, the right side elevation view and the left side elevation view are mirror images of this view;

FIG. 7 illustrates a top view of FIG. 5; and,

FIG. 8 illustrates a bottom view of FIG. 5.

The word "BOOST," forming part of an embodiment of the claimed design, is a registered trademark of Societe Des Produits Nestle, S.A., Vevey, Switzerland.
